US0D1076173S

(12) **United States Design Patent** (10) Patent No.: **US D1,076,173 S**
(45) Date of Patent: ** May 20, 2025

(54) **CURVED MONITOR LAMP**

(71) Applicant: **Shenzhen Yuanrunxin Electronics Co., Ltd.**, Shenzhen (CN)

(72) Inventors: **Tao Yang**, Shenzhen (CN); **Cheng Chen**, Shenzhen (CN); **Yuanlian Huang**, Shenzhen (CN); **Guowu Huang**, Shenzhen (CN); **Fang Chen**, Shenzhen (CN)

(73) Assignee: **Shenzhen Yuanrunxin Electronics Co., Ltd.**, Shenzhen (CN)

(**) Term: **15 Years**

(21) Appl. No.: **29/974,399**

(22) Filed: **Nov. 22, 2024**

(51) LOC (15) Cl. **26-05**

(52) U.S. Cl.

USPC **D26/61**

(57) **CLAIM**

The ornamental design for a curved monitor lamp, as shown and described.

DESCRIPTION

FIG. 1 is a top perspective view of a curved monitor lamp, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is a top perspective view of the curved monitor lamp in an alternate configuration of use.

The broken lines in the drawings illustrate the portions of the curved monitor lamp, which form no part of the claimed design.

1 Claim, 9 Drawing Sheets
